A. STORBACKA

WATER TURBINE

Filed March 18, 1925

FIG. 5

PFR

Albert J. Fike

ATTORNEY.

UNITED STATES PATENT OFFICE.

ARNE STORBACKA, OF VANCOUVER, BRITISH COLUMBIA, CANADA.

WATER TURBINE.

Application filed March 18, 1925. Serial No. 16,294

This invention relates to improvements in water or other fluid turbines, and has for one of its principal objects the provision of a turbine adapted to be operated by the force 5 of running water or the like, and which will more efficiently utilize the potential and kinetic energy available.

One of the important objects of this invention is to provide, in a water turbine or 10 the like, means for efficiently and accurately controlling the flow of water through the turbine itself with a view to utilizing power as desired.

Another important object of the invention 15 is the provision, in a water turbine or the like, of a novel and more efficient form of rotor, which will more effectively utilize the kinetic energy of the running water and which will at the same time provide for a 20 proper distribution and elimination of spent water by means of centrifugal force.

Still another and further important object of the invention is to provide, in a water turbine or the like, means for delivering 25 several distinct elements or streams of water to a rotor provided with blade-like faces, so that the resultant efficiency of the turbine will be greater than that heretofore obtained.

Other and further important objects of 30 the invention will be apparent from the disclosures in the accompanying drawing and following specification.

The invention, in a preferred form, is illustrated in the drawings and hereinafter 35 more fully described.

In the drawings:

Figure 1 is a vertical sectional view of the improved turbine of this invention, the 40 rotor thereof being indicated in elevation.

Figure 2 is a sectional view, taken on the line 2—2 of Figure 1, looking in the direction indicated by the arrows.

Figure 3 is a sectional view, taken on the 45 line 3—3 of Figure 1, looking in the direction indicated.

Figure 4 is a side elevation illustrating a modification of the turbine itself.

Figure 5 is a perspective view showing 50 the improved rotor of the invention.

As shown in the drawings:

The reference numeral 10 indicates generally a casing or the like forming the main body of the improved water turbine of this 55 invention. As illustrated in Figure 1, the casing 10 is adapted to be attached or se-

cured to the outer face of the wall of a dam or the like 12, behind which is maintained a body of water 14.

As best illustrated in Figures 1 and 2, the 60 rear portion of the casing 10 is in the form of a disk 16 having a number of openings therethrough and adapted to co-operate with the disk 16 is a complementary rotatable gate element 18 having a rack 20 formed in a portion of its periphery, with which rack co- 65 operates a worm wheel 22 mounted on an operating shaft 24 adapted to be manually controlled by means of a hand wheel or the like 26. The hand wheel 26 is, as shown in 70 Figure 1, positioned adjacent the top of the dam 12. In this way the flow of water to the turbine itself can be accurately and effectively controlled and regulated.

The main body casing 10 is formed with 75 a plurality of spiral passages 28 therein, as best indicated in Figure 1, these passages leading from a common opening and terminating at various points adjacent the forward end of the casing and adapted to deliver the water passing therethrough directly 80 onto the blade-like surfaces of a rotor 30 formed in the shape of a frustum of a cone, as indicated in Figures 1 and 5. The rotor may be made hollow for purposes of light- 85 ness, but the ends are closed to prevent undesired passage of water therethrough. The relation between the nozzles or outlets of the passages 28 and the blades 32 of the rotor 30 is such that the water issuing from the 90 opening 28 will impinge upon the blades 32 at substantially right angles, thereby affording the greatest possible measure of efficiency.

As will be noted, the larger base of the 95 rotor 30 is positioned adjacent the outlet of the casing 10, thereby providing for a ready elimination of spent water, the same being thrown off and outwardly by the centrifugal force developed by the rotation of the 100 rotor itself.

A suitable outlet nozzle or the like 34 is provided attached to the casing 10 by means of bolts and nuts 36 or the like, and in this outlet nozzle 34 is positioned a suitable bearing 38 provided for supporting one end of a shaft 40 upon which the rotor 30 is mounted, the other end of the shaft 40 being positioned in suitable bearings 42 in the casing 10. Attached to the inner end of the shaft 40 is a beveled gear 44 which co-operates with a similar beveled gear 46 mounted on

the vertical shaft 48, whereby the power generated by the rotation of the rotor 30 can be conveniently taken off and utilized.

In the illustration shown in Figure 1, the 5 casing 10 is adapted to be mounted upon the base or bed of a stream or the like by means of suitable supports 50, and the modification illustrated in Figure 4 discloses a similar turbine embodying a casing 10, an outlet nozzle 34, and operating elements adapted to be supported at any suitable height above the bed of a stream by means of shoring or the like 52. Further, proper connecting means comprising a flange 54 and 10 retaining nuts 56 are provided adapted to maintain the casing 10 in suitable and desired position with respect to a dam or other retaining wall.

I am aware that many changes may be 20 made and numerous details of construction

varied throughout a wide range without departing from the principles of this invention, and I therefore do not purpose limiting the patent granted hereon otherwise than as necessitated by the prior art.

25

I claim as my invention:

In a fluid turbine, the combination of a casing, a frustro-conical rotor in the casing, a plurality of blades integral with the rotor and spirally arranged thereon, and means 30 for conveying and directing fluid to the rotor, said means including passages spirally arranged in the casing, together with means for regulating the flow of water through said passages, said means comprising an 35 apertured disk integral with one end of the casing, and a co-operating rotatable similarly apertured disk adjacent thereto.

In testimony whereof I affix my signature.

ARNE STORBACKA.
